UNITED STATES PATENT OFFICE.

ROBERT LUNDELL, OF NEW YORK, N. Y., ASSIGNOR OF TWO-THIRDS TO
THE SPRAGUE ELECTRIC COMPANY, OF SAME PLACE.

ELECTRIC MOTOR.

SPECIFICATION forming part of Letters Patent No. 626,708, dated June 13, 1899.

Application filed July 16, 1898. Serial No. 686,184. (No model.)

To all whom it may concern:

Be it known that I, ROBERT LUNDELL, a citizen of the United States, residing at New York, in the county of New York and State 5 of New York, have made a new and useful Invention in Electric Motors, of which the following is a specification.

My invention is directed in particular to improvements upon electric motors disclosed 10 in prior patents of mine, No. 481,701, granted August 30, 1892, and No. 587,531, granted August 3, 1897; and its objects are, first, to provide simple and efficient means for detachably securing the commutator-brushes in place and 15 connecting the same with the ends of the current-carrying wires or conductors, and, second, to provide simple and efficient means for securing the fan-protecting frame to the body of the motor and its supporting-standard.

20 My invention will be fully understood by referring to the accompanying drawings, in which—

Figure 1 is a broken sectional view taken through the body of the motor and the fan-protecting frame, the armature-shaft being shown in side elevational view and the rotary fan attached to one end thereof in dotted lines. Fig. 2 is a transverse sectional view taken through the body of the motor and one of the commutator-brushes and its supporting and attached parts, the armature, the fan-protecting frame, and the fan being removed. Fig. 3 is an enlarged longitudinal sectional view taken through the body of one of the commutator-brushes and its supporting and attached parts, the inleading wire being disconnected therefrom, the commutator against which the brush rests being shown in part elevational view.

Fig. 3^a is a detail plan view of one of the inleading wires and the yielding forked metallic end which holds the commutator-brush in place. Fig. 4 is an end elevational view of the entire motor and the fan-protecting frame, the fan being shown in dotted lines, all as 45 seen looking at Fig. 1 of the drawings, from the left toward the right hand side thereof.

Referring now to the drawings in detail and first to Fig. 1, P P' represent duplicate or interchangeable parts of the field-magnets, having overlapping field-magnet poles surround-

ed by an energizing field-magnet coil, the axis of which is inclined at an angle to the armature-shaft C, supported in journal-bearings J J, (see Fig. 2,) cast in removable end plates R R', the armature being supported by said 55 shaft between the overlapping field-magnet poles. The end plates R R' are each provided with one or more pairs of bolt-holes, adapted to receive corresponding bolts B B, made, preferably, of non-magnetic material, such as 60 brass, and provided with nuts N N. (See Fig. 2.)

d d are dowel-pins located in drill-holes in the inner faces of the duplicate or interchangeable parts P P', and d' d' d' d' are corresponding 65 dowel-pins located in drill-holes in the outer faces of said parts and also in corresponding drill-holes in the end plates R R', the entire arrangement being such that when the field-magnet coil is put in place over the overlapping pole-pieces, the armature and its connected commutator V, carried by the shaft C, slipped into position, and the opposite ends of the shaft inserted through the journal-bearings J J in the end plates R R', all of said 75 parts are securely held together by the dowel-pins d d d' d', bolts B B, and nuts N N.

It will be apparent on inspection of Fig. 2 of the drawings that the several parts of the field-magnet frame of the motor are held together by the action of the bolts B B upon the end plates R R' and that said bolts pass through openings between the shell-like portions P P' of the body part of the field-magnet and the overlapping field-magnet poles, 85 thereby avoiding the necessity of drilling or otherwise weakening any portion of the field-magnet proper.

o o o o represent radially-disposed slots or openings in the end plates R R' for the purpose of affording ventilation to the interior of the motor, the slots or openings in the plate R' affording also a means for observing the operation of the commutator V and the brushes bearing thereon.

W W' represent vertically-arranged oil-wells drilled in the outer or extended ends of the end plates R R' and substantially at right angles to the journal-bearings J J, which support the armature-shaft C, and T T represent 95 100

oil-grooves located near the inner ends of said journal-bearings, which grooves are connected to their corresponding oil-wells by downwardly-extending ducts Q.

5 O represents a lubricant in each of the wells W W', and w' represents fibrous material, such as waste cotton, adapted to convey the oil by capillary action to the ends of the journal-bearings J J, the arrangement being such 10 that as the lubricant is carried upward and advances inward toward the armature it ultimately descends by way of the grooves T and ducts Q to the wells W', thus providing means for preventing it (the lubricant) from in any 15 way coming into contact with the operative parts of the motor and affording a means for continuously lubricating the bearings.

M M represent removable caps or covers 20 for the oil-wells, secured by chains to the end plates R R'.

S represents a hollow metallic standard provided with three or more legs L' L' L', adapted to receive rubber cushions in their under surfaces, as shown. Through the upper 25 part of said standard are drilled screw-holes, adapted to receive screws s' s', extending into corresponding screw-holes in the duplicate or interchangeable parts P P', their function being to detachably secure the standard S in said parts.

C' represents a curvilinear protecting rim or cup at the top of the standard, adapted to surround or protect the opening through which the wires W W pass downward and to give to the structure a neat or compact appearance when the supporting-standard is secured to the body part of the motor, as described.

40 L represents the control-switch, pivotally secured beneath the bottom of the standard and operatively connected with the usual rheostat, to which the lower ends of the wires w w are connected in a well-known manner.

I I represent insulating-sleeves secured by 45 set-screws Z in transverse openings entering the end plate R'.

S' S' represent metallic guiding-sleeves secured by pins p p to the inner side of the insulating-sleeves I I, the function of said sleeves S' being to act as conducting-guide-ways for the commutator-brushes CB CB, 50 preferably of carbon and of cylindrical form and recessed at their outer ends for the purpose of securing thereto the inner ends of compressible conducting-springs S² S².

K K are detachable caps each provided with a drill-hole e of substantially the same diameter as the corresponding drill-holes in the outer ends of the sleeves S' S'. The removable caps K K are recessed after the same manner as are the outer ends of the carbon brushes CB CB for the purpose of receiving the outer or free ends of the compressible conducting-springs S² S².

65 J' represents a metallic sleeve secured to the free end of the inleading wire running from

the source of current-supply (not shown) and provided at its free end with a pair of yielding metallic arms t t, adapted to offer considerable frictional resistance when inserted 70 through the holes e of the caps K and the corresponding holes in the sleeves S', when said caps are pressed downward and the springs S² put under compression, all as shown in Fig. 2, thereby causing the commutator-brush to rest yieldingly against the commutator V and to advance as they are worn away in substantially the same manner as do the commutator-brushes in connection with the motor disclosed in my prior patent, No. 481,701, 80 above referred to, this part of my improvement being directed to a simple and efficient manner of affording access to the commutator-brushes disclosed in the aforesaid patent.

R² R³ R⁴ represent metallic rings which 85 constitute the body of the fan-protecting frame, said rings being held together by radially-disposed curvilinear wires D D, said protecting-frame in itself being a well-known structure and not herein claimed by me, the only feature of novelty in this particular being directed to the means of supporting the frame, which means consists of lugs G G, secured to the inner rings R², which in turn are secured by screws s' s' to flattened surfaces E E near 90 the base of the standard S, the upper side of the fan-protecting frame being secured by a downwardly-extending arm F, attached to the inner ring R², its lower end being bent at an angle and secured to the duplicate or interchangeable parts P P' by screws s s, extending 95 downward through drill-holes in a metallic eye H, which serves the double function of securing the arm F in place and also affords a means for suspending the motor by a 100 cord or chain or for moving it by hand from place to place.

Prior to my improvement it was customary to sustain the protecting-frames of rotary electric fans by arms running from the inner surface of the frame radially toward the body of the motor itself, and the especial feature of novelty in my improvement lies in supporting the lower side of the protecting-frame directly upon the standard which supports the motor 110 and the upper portion thereof by an arm running to the body of the motor-frame, such an arrangement affording much greater rigidity than was possible with supporting means running radially toward the body of the motor 115 120 itself.

Having thus described my invention, what I claim, and desire to secure by Letters Patent of the United States, is—

1. An electric motor provided with commutator-brushes inclosed each in a guiding-sleeve having a transverse opening at its outer end, in combination with a yielding spring one end of which is adapted to bear on the outer end of the brush and a removable cap adapted 125 to bear against the outer end of the spring, said cap being provided with an opening cor- 130

- responding to the opening in the sleeve and adapted to be in alinement therewith when forced into position within the sleeve, substantially as described.
- 5 2. An electric motor provided with commutator-brushes inclosed each in a guiding-sleeve having a transverse opening at its outer end, in combination with a yielding spring one end of which is adapted to bear on the outer 10 end of the brush, and a removable cap adapted to bear against the outer end of the spring, said cap being provided with an opening corresponding to the opening in the sleeve and adapted to be in alinement therewith when 15 forced into position within the sleeve, together with an inleading wire or conductor provided with yielding metallic arms adapted to enter the openings in said sleeve and cap, substantially as described.
- 20 3. An electric fan-motor having a supporting-standard for the body of the motor, in combination with a protecting-frame for the fan, together with means for securing said frame to the supporting-standard and additional means for securing it to the top part of 25 the body of the motor, substantially as described.
4. An electric fan-motor having a supporting-standard for the body of the motor, in combination with a protecting-frame for the 30 fan; together with lugs G G secured to the protecting-frame and to the base of the supporting-standard, in combination with an arm extending from the top of said frame to the top part of the body of the motor and secured 35 thereto by a metallic eye H and screws s s, substantially as shown and described.
5. An electric fan-motor having a supporting-standard for the body of the motor, in combination with a protecting-frame for the 40 fan, together with means for securing said frame to the supporting-standard; and additional means for securing it to the body part of the motor, substantially as described.

In testimony whereof I have hereunto subscribed my name this 6th day of July, 1898.

ROBERT LUNDELL.
